UNITED STATES PATENT OFFICE.

HENRY A. WISE WOOD, OF NEW YORK, N. Y., ASSIGNOR TO THE CAMPBELL PRINTING PRESS & MANUFACTURING COMPANY, OF NEW YORK, N. Y., A CORPORATION OF NEW YORK.

PRINTING-MACHINE.

SPECIFICATION forming part of Letters Patent No. 694,597, dated March 4, 1902.

Application filed May 31, 1895. Serial No. 551,290. (No model.)

To all whom it may concern:

Be it known that I, HENRY A. WISE WOOD, a citizen of the United States, residing at New York, in the county of New York and State of New York, have invented a new and useful Improvement in Printing-Machines, of which the following is a specification.

The aim of this invention is to provide a new and improved printing-machine of the class known as "reciprocating-cylinder printing-machines," which is especially adapted for color-printing, as hereafter described; and to this end the invention consists of the device described and claimed in this specification and illustrated in the accompanying two sheets of drawings, in which—

Figure 1 is a side elevation of enough of a printing-press embodying my improvement to illustrate the same. Fig. 2 is a plan of the same. Fig. 3 is a sectional elevation on the line 3 3 of Fig. 2. Fig. 4 is a sectional elevation on the line 4 4 of Fig. 2. Fig. 5 is a sectional elevation illustrating a modification. Fig. 6 is a plan view illustrating a further modification; and Figs. 7 and 8 are sectional elevations on the lines 7 7 and 8 8 of Fig. 6, respectively.

Referring to the drawings and in detail, 1 and 2 designate the usual side frames of a machine, and between these side frames are arranged form-beds A and B, which are substantially twice the width of the web to be printed. On the side frame 1 is arranged a guide or gib 5, and a similar gib 6 is arranged on the side frame 2. Fitting on the gib 5 is a yoke 7, and a similar yoke 19 fits on the guideway 6. The yoke 7 has in the vertical portion thereof a vertical slot 8, as shown, and fitting in this vertical slot is a square block 10, which is journaled on a wrist-pin 9, carried by the gear 11. This gear 11 is mounted on a shaft 12, which is journaled in the main framing, and on the opposite end of the shaft 12 is fastened a crank-arm 15, which has a crank-pin 16, which carries a square block 17, which fits in a slot in the yoke 19. The gear 11 is driven by means of pinion 14, mounted on shaft 13, and this shaft 13 may be the shaft to which power is applied to operate the machine.

Extending up from the yoke 7 are brackets 20, and extending up from the yoke 19 are brackets 21. Journaled in these brackets 20 and 21 are impression-cylinders C and D, which are adapted to coact with forms placed upon the stationary beds. It will be seen that as the gear 11 and crank-arm 15 are revolved the wrist-pins will communicate a reciprocating motion to the cylinders, and this reciprocating motion will be a very smooth and easy one, as no pitmen are used. This driving mechanism for the impression cylinder or cylinders is applicable to any form of reciprocating-cylinder printing-machines. Mounted between the brackets 20 and 21 are rods or shafts 22, 23, 24, and 25. As hereafter described, the web is led twice around each impression-cylinder, so that when the same is pulled or fed forward the web will move oppositely around these parts.

The rods 22, 23, 24, and 25 preferably are rigidly mounted between the brackets 20 and 21. On these rods are fastened suitable collars 30, and between these collars 30 are mounted rollers E, whereby when the web is pulled forward it can turn these rollers on each of said rods in different directions.

Between each of the brackets 20 and 21 are arranged suitable inking-rollers I I, to which ink may be supplied in any of the usual ways and which are adapted to ink the forms.

From the shaft 13 power is transmitted to a longitudinal shaft 43 by means of a pair of bevel-gears 420. The shaft 43, by means of a bevel-pinion 44 and a bevel-gear 45, turns shaft 48 and also, by means of bevel-gears 49 and 50, turns vertical shaft 51. This vertical shaft 51, by means of bevel-gears 52 and 53, turns rollers 34, 35, and 36, which are geared together.

On the shaft 48 are arranged suitable cams 46, and bearing on these cams are arms 39, which may be mounted in the main frame and the lower ends of which may be forked to straddle the shaft 48. These arms 39 have rollers 42 bearing against the face of the cams in the ordinary manner. Springs 47 are used to keep the arms normally in their lowest position and the rollers 42 against the cams 46. Journaled in these arms 39 are suitable roll-

ers 37 and 38, which perform the function of looping - rollers, as hereafter described. These looping-rollers 37 and 38 coöperate with rollers 40 and 41, mounted on the frame, 5 as shown.

- On the right-hand end of the press are mounted two turner-bars 31 and 32, arranged in the same horizontal plane, which are adapted to deflect the web, so that the same 10 may pass again around the impression-cylinders and be again printed thereby, whereby the machine as organized in Figs. 1 and 2 forms a four-color-printing machine. It will be seen that the deflector device is arranged 15 in substantially the same horizontal plane as the guide 25. By this arrangement the web may pass from and back to the impression-cylinder without intermediate guides and can be manipulated with slight strain.
- 20 The path of the web through the machine is as follows: A web-roll 54 is mounted in any of the usual manners near the end of the press, and from this roll the web is led up over the continually-running roller 34, under 25 the roller 35, and up over the roller 36, then over roller 40, down under looping-roller 38, up over roller 41 to the guide 22, carried by the moving carriage, then around impression-cylinder C, up over guide 23, across to the guide 24, under the impression-cylinder D, up over 30 the guide 25, and then up over the turner-bar 31, laterally across the press, and then down over the turner-bar 32 back into the press, parallel with its former path. It will be seen 35 that as the web runs over this turner or deflector device the same will be transferred laterally and will assume a pathway parallel with its original direction. It will also be seen that the printed side of the web will not 40 touch either turner-bar 31 or 32. Hence there will be no smut on the printed side of the web.

Referring now to Fig. 4, it will be seen that the web from the turner-bar 32 is led back over guide 25, around impression-cylinder D, 45 over guide 24, to guide 23, around impression-cylinder C, up over guide 22, under guide 41, up over looping-roller 37, under the guide 40, then under the continually-running roller 36, up over the roller 35, and down under the 50 roller 34, which will act to deliver the web from the press, and it will be seen that the same set of continually-running rollers will feed the web both into and out of the press.

With a press thus organized the sheet can 55 be given four impressions in as many colors, and hence the machine is what is technically known as a "four-color-printing" machine. The looping-rollers 37 and 38 are so timed that while the cylinders are in impression they 60 will take up the web unwound from the roll 54 by the continually-running rollers and will pay the web out to the rollers 34, 35, and 36; but as the cylinders reverse in either direction the web will be shifted the length of a 65 sheet. The press is thus organized to print two complete sheets for each forward-and-backward reciprocation of the impression-cyl-

inders. The impression-cylinders are geared to racks on the side frames, as shown, whereby they will turn and always be kept in register with the forms. 70

Half of my machine may be used to print two colors, the web being fed through the press in one direction only. This can be done as shown in the diagram in Fig. 5, in which instead of turning the web back parallel to its original pathway the web from the guide 25 is carried out by guide 410 over a looping-out roller 310, up over a guide-roller 400, and then into the bite of feeding-out rollers 360, 370, and 380, which may be continually driven to feed the web out of the press. Of course it is understood that this feeding-out or delivery device would be simply added to the press shown in the first sheet of 85 the drawings without changing any of the parts shown in Figs. 1 and 2.

Another way in which I may use the press shown in the first sheet of the drawings for two-color work is to lead the web through the 90 press so that the same will not pass under two of the impression-surfaces. For instance, I could lead the web from the turner 32 directly to the roll 41, thus utilizing the parts of the impression-cylinders next to the frame 95 1, or I could lead the web from the roll 40 directly to the first bar 31 of the turner, and thus utilize only the other half of the impression-cylinders, or, further, I could use either or both impression-cylinders simply by not 100 leading the web under the parts of the impression-cylinders which it is desired to omit, or I could use my press as a three-color press by simply leading the web so as not to pass under one-half of one of the impression-cylinders. 105

It will be seen that the guides travel with the impression-cylinders, and each set thereof is so arranged that the web could be led from one directly to the other without looping or 110 passing the same down under the impression-cylinder.

Another way in which a two-color machine may be arranged is as shown in Figs. 6, 7, and 8. In this case only one impression-cylinder F 115 is used and only one bed G. The web is led from the roll to this cylinder in the same manner as it is led to the cylinder C of the previous device and then is led directly to the deflector device and is directed back parallel 120 with its original pathway, again around the impression-cylinder F, and delivered from the press by the looping-roller 37 and the rollers 34, 35, and 36, as before described. It will be seen that the web-manipulating device is 125 arranged at the opposite end of the machine relatively to the deflector, whereby the operative and moving parts can be very simply and easily adjusted and nicely operated. The particular web-manipulating mechanism, as 130 before described, consists of means for continuously feeding the web into and out of the press and a device, as the loopers, for respacing the web. Other forms of web-manipulat-

ing devices to properly shift the web in the machine at the right time may be used. A press as thus organized comprises a very neat and simple two-color machine and illustrates 5 the simplest form of this present invention.

The details herein shown and described are not exact details of the working device, as in a practical machine some of the rollers would have to be made adjustable for register; but 10 these details are omitted, as they are so well known to the ordinary printing-press mechanic that they can be easily supplied in the practical machine.

It is understood, of course, in describing 15 the operation of the machine that a form is placed upon each bed, and it is understood, of course, that ink is supplied to the inking-rollers so that, if desired, these forms can receive different-colored inks.

20 The arrangement of parts herein shown and described may be greatly varied by a skilled mechanic without departing from the scope of my invention as expressed in the claims.

Having thus fully described my invention, 25 what I claim, and desire to secure by Letters Patent, is—

1. The combination in a printing-press of a stationary form-bed, a traveling impression-cylinder coacting therewith, guides for directing a web to and from the traveling impression-cylinder, a deflector device arranged at one end of the machine to deflect the web after the same has been once printed back parallel with its original pathway and with the 35 same side uppermost, again under the impression-cylinder, whereby the same side of the web can be twice presented to the forms by the same traveling impression-cylinder, and a web-manipulating device arranged at 40 the other end of the machine relatively to the deflector for respacing the web when the impression-cylinder is out of impression.

2. The combination in a printing-press of a stationary form-bed, a traveling impression-cylinder coacting therewith, guides for directing a web to and from the traveling impression-cylinder, a deflector device arranged at one end of the machine to deflect the web after the same has been once printed back 45 parallel with its original pathway, and with the same side uppermost, again under the impression-cylinder, whereby the same side of the web can be twice presented to the forms by the same impression-cylinder, and means 50 for continuously feeding the web into and out of the press, and for respacing the web arranged at the other end of the machine relatively to the deflector, for shifting the web when the impression-cylinder is out of impression.

60 3. The combination in a printing-press of two stationary form-beds, a traveling impression-cylinder coacting with each form-bed, a deflector device arranged in the path of the web beyond the second of said impression-cylinders, guides for directing a web around both impression-cylinders, then around the

deflector, then parallel with its original pathway, again around the two impression-cylinders, whereby a multicolor-printing machine 70 is provided, and a web-manipulating device arranged to shift the web when the impression-cylinders are out of impression.

4. The combination in a printing-press of two stationary form-beds, a traveling impression-cylinder coacting therewith, a deflector device arranged at one end of the machine, guides for directing a web around said impression-cylinders, then through the deflector device, then back parallel to its original pathway, again around the impression-cylinders with the same side uppermost, whereby a multicolor-machine is provided, and a web-manipulating device arranged at the other end of the machine relatively to the deflector, 80 85 for shifting the web when the impression-cylinders are out of impression.

5. The combination in a printing-press of a stationary form-bed, a traveling impression-cylinder coacting therewith, a guide moving 90 with the impression-cylinder at each side thereof, a stationary deflector device arranged in the path of the web beyond the traveling impression-cylinder, and in substantially the same horizontal plane as the guide on the side 95 of the impression-cylinder next to said deflector, the whole arranged to direct the web back parallel to its original pathway, again under the impression-cylinder with the same side uppermost, and a web-manipulating device arranged at the other end of the machine relatively to the deflector for shifting the web when the impression-cylinder is out of impression.

6. The combination in a printing-press of 105 two side frames, a yoke mounted to reciprocate on each of said side frames, each of said yokes having a vertical slot, a revolving wrist-pin engaging each of said slots, brackets carried by said yokes, an impression-cylinder 110 mounted in said brackets, suitable web-guides and web-manipulating devices.

7. The combination in a printing-press of two side frames, a yoke mounted to reciprocate upon each of said side frames, each of 115 said yokes having a vertical slot, revolving wrist-pins engaging said vertical slots, brackets carried by said yokes, two impression-cylinders journaled in said yokes, suitable web-guides and manipulating mechanism.

8. The combination in a printing-press of a form-bed, a traveling impression-cylinder coacting therewith, a deflector, and devices for leading a web under said impression-cylinder in opposite directions, and guides for said web 125 arranged at each side of the impression-cylinder having independent portions thereof adapted and arranged so that they may turn in opposite directions.

9. The combination in a web-printing press 130 of two form-beds, a traveling impression-cylinder cooperating with each bed, a deflector, and guides for leading a web twice around each cylinder, said guides constructed so that

different parts of the same may turn independently of each other, and web-manipulating mechanism.

10. The combination in a web-printing press of a form-bed, a traveling impression-cylinder coacting with said form-bed, a deflector, guides for leading a web around said impression-cylinder, through the deflector, and back parallel to its original pathway around said impression-cylinder so that the same side of the web will be twice presented to the forms by said impression-cylinder, a pair of looping-rollers over which the web is oppositely looped before and after passing to the impression-cylinder, and a continuously-running feeding device through which the web is led both before and after passing from said loopers, so that the same can be continuously fed into and out of the press by the same device.

11. The combination in a web-printing press of two form-beds, a traveling impression-cylinder coacting with each form-bed, a deflector, guides for leading a web around each impression-cylinder, then around the deflector, then back parallel to its original pathway, again around said impression-cylinders, so that said web may have the same side thereof presented to the forms four times by said impression-cylinders, a pair of loopers arranged at the opposite end of the machine from the deflector, and a continuously-running feeding device through which the web is led to and from said loopers, whereby the same device can feed the web into and out of the machine.

12. In a traveling-cylinder web-printing press, the combination of two form-beds, two traveling cylinders coöperating therewith, means for constantly unwinding the web from the web-roll, means for constantly delivering the web from the machine, means for intermittently respacing the web with respect to the form-beds and a deflector for directing the web twice over the form-beds, whereby the web may be printed four times.

13. In a traveling-cylinder multicolor web-

printing press, the combination of two form-beds, two traveling impression-cylinders co-operating therewith, guides arranged at each side of each cylinder, the web passing from one cylinder to the other so that said cylinders will present the same side of the web to be printed, means for feeding the web into and out of the machine, and for respacing the same around the impression-cylinders when they are out of impression.

14. In a traveling-cylinder multicolor web-printing press, the combination of two form-beds, two traveling impression-cylinders co-operating therewith, guides at each side of each cylinder moving therewith, the web being led from one impression-cylinder to the other, so that said impression-cylinders will present the same side of the web to the forms, means for continuously unwinding the web from the web-roll, means for continuously delivering the web from the machine, and means for intermittently respacing the web with respect to the form-beds when the cylinders are out of impression.

15. In a traveling-cylinder multicolor web-printing press, the combination of two stationary form-beds, a traveling impression-cylinder coöperating with each form-bed, guides at each side of each cylinder moving therewith, a deflector arranged in the path of the web beyond the second of said cylinders, so that the web may be deflected and led a second time around said cylinders parallel with its original pathway, means for continuously unwinding the web from the web-roll, means for continuously delivering the web from the machine, and means for intermittently respacing the web with respect to the form-beds when the cylinders are out of impression.

In testimony whereof I have hereunto set my hand in the presence of two subscribing witnesses.
